(57) **CLAIM**

The ornamental design for a self defense protection device, as shown and described.

DESCRIPTION

FIG. 1 is a top perspective view of the self defense protection device showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a view showing the self defense protection device worn on a hand.

The broken line showing depicts environmental structure and is included for the purpose of illustrating only and forms no part of the claimed design.
